DEVICE FOR SUPPORTING STAGE CURTAINS
OR THE LIKE

David A. Washburn, New Haven, Conn.

Application December 18, 1940, Serial No. 370,700

13 Claims. (Cl. 156—46)

This invention relates to means for supporting a curtain or the like such as a stage curtain or drop, and more particularly to the provision of means by which a stage curtain or cyclorama may be suitably supported upon a flexible overhead track and rolled up horizontally upon a drum the axis of which extends in a vertical direction so that the curtain will hang freely and smoothly upon the drum.

The supporting device includes a horizontally extending track which suitably guides as well as supports the free end (the end remote from the drum) of the curtain so that the latter may have a sinuous or other form in a horizontal direction if desired, and at the same time be properly guided so that it may be readily rolled up or extended without inconvenience.

In the past considerable difficulty has been encountered in handling stage curtains or drops of relatively large size. The construction of a tower above the stage into which the curtains are raised entails a considerable expense, and the present invention provides for the rolling up of the curtain upon a vertical drum, which, while sufficiently large so that the curtain will not be damaged, requires a relatively small floor space.

One object of the invention is the provision of a novel supporting means for a rolling curtain or cyclorama.

Another object of the invention is the provision of a supporting device for a rolling curtain or cyclorama provided with a vertically extending drum upon which the curtain may be rolled in a horizontal direction.

A further object of the invention is the provision in a device of the character described of a guiding track for the curtain or cyclorama, such that the latter may be adjusted to change the horizontal direction or shape of the curtain.

A still further object of the invention is to provide a cable-supported curtain and a novel means for suitably supporting and guiding the cable, and in addition novel means for supporting the curtain from the cable so that it may be properly rolled upon a drum in a horizontal direction.

A still further object of the invention is the provision of a cable-supported curtain having a web to which the curtain is secured, which web is in turn secured to a flexible cable, and which web is cut on the bias so that, while it may not move parallel to the center axis of the cable, it may rotate or move around the cable owing to stretching of the web, and which bias-cut supporting webbing will also permit the proper roll-

ing up of the curtain on a winding drum, regardless of the difference in diameter caused by the overlapping of the folds upon the drum.

To these and other ends the invention consists in the novel features and combinations of parts to be hereinafter described and claimed.

In the drawings:

Fig. 1 is a front elevational view of a supporting and operating device for a stage curtain or cyclorama embodying my invention;

Fig. 2 is a sectional view on line 2—2 of Fig. 1;

Fig. 3 is a front elevational view of the winding drum and associated parts, some of which are shown in section;

Fig. 4 is a fragmentary front elevational view of the upper portion of the curtain and the supporting means therefor;

Fig. 5 is a sectional view on line 5—5 of Fig. 4;

Fig. 6 is a fragmentary front elevational view of one of the horizontal seams of the curtain;

Fig. 7 is a sectional view on line 7—7 of Fig. 6;

Fig. 8 is an enlarged top plan view of a portion of the flexible track;

Fig. 9 is a view similar to Fig. 8, showing the parts of the track adjusted to a different position or shape;

Fig. 10 is a side elevational view of the parts shown in Fig. 8; and

Fig. 11 is a sectional view on line 11—11 of Fig. 10.

To illustrate a preferred embodiment of my invention, I have shown a drum-supporting frame designated generally by the numeral 10, which frame may be in turn supported by cables or rods 11 attached to the ceiling or other overhead structure. This frame comprises a downwardly extending member 12 to which the curtain track is secured, as will be hereinafter described.

Upon the frame 10 are mounted suitable collars or the like 13 and 14, through which extends rotatably the shaft 15 of the winding drum 16. The shaft 15 may be rotated by any suitable means, a crank 17 being shown herein for this purpose, but it will be understood that the device may be motor-operated if desired. Within the collar 14, as shown in Fig. 3, is secured a nut 18 which is internally threaded to cooperate with the threads 19 on the shaft 15, so that as the shaft is rotated it, together with the drum 16, will be raised and lowered according to the pitch of the threads. As will be hereinafter explained, the curtain is supported upon a cable or rope, and the pitch of the threads is so proportioned relatively to the diameter of the cable that the

drum will be raised or lowered a sufficient amount to enable one turn of the cable to lie directly above the other against the surface of the drum.

The frame 10 may be suitably anchored laterally by guy ropes or wires 20 and 21. Also rotatably carried by the frame 10 is a shaft 22 carrying at its lower end a roller 23 designed to hold the curtain-supporting cable against the supporting drum 16, as will be hereinafter explained, the roller 23 being an idler roller and being driven merely by contact with the curtain or supporting cable.

The construction of the drum 16 is shown more particularly in Fig. 3, from which it will be seen that the drum is relatively short compared to the height or vertical dimension of the curtain, and is provided at its lower end with a portion of greater diameter so as to provide an annular upwardly facing shoulder 25, and is provided intermediate its length with a second annular shoulder 26, these shoulders being provided to support the curtain-supporting cable and prevent the latter from slipping downwardly upon the drum. Also upon the shaft 15 below the winding drum 16 is a second drum 27 adjustable longitudinally of the shaft 15 and retained in any desired adjusted position by a set screw 28 passing through a collar 29 secured to the portion 27. This lower adjustable drum portion is designed to be adjusted to the proper position so that it will hold the folds of the curtain in circular form, as these folds depend from their supported upper margins above the shoulder 25. The particular position of adjustment of the drum portion 27 will depend upon the characteristics of the curtain employed, it being desirable to hold the folds of the curtain in smooth circular form as they hang from the drum.

As has been stated, the curtain is supported upon a cable 30 to which it is secured, as will be hereinafter explained. This cable passes around a pulley 31 secured at the end of the flexible curtain-supporting track, as will be hereinafter explained, and the free ends are passed through openings 32 and 33 in the drum and there secured to the latter, so that, as the drum rotates, the ends of the cable will be wound thereupon or unwound therefrom, as the case may be. As shown more particularly in Fig. 2, one end of the cable passes about one side of the drum, and the other end passes about the other side, so that they will be wound upon the drum in opposite directions. Therefore, when the drum rotates the cable at one end will be wound upon the drum, and at the other end unwound therefrom, the bight portion passing freely through the pulley 31.

The manner of supporting the curtain or cyclorama from the cable will now be described. As shown more particularly in Figs. 4 and 5, a piece of heavy webbing such as canvas, for example, 35, is looped over or wrapped around the cable, and the edge portion secured as by the stitching 36. This material is preferably secured to the cable in some way such as by a layer of adhesive 37 to prevent movement of the web longitudinally of the cable. The strip 35 is preferably cut on the bias so that the threads will run at an angle of approximately 45° to the horizontal. The use of a bias-cut webbing permits the webbing to stretch when rolled upon the drum 16, and particularly over the annular shoulder 25, so that, while the diameter of the roller of the curtain at this point will, due to the overlapping of the several folds, be

greater than the diameter of the circular coil of the cable 30 which lies next to the drum, nevertheless the strip of webbing and curtain supported thereby will lie flatly and smoothly in a circular roll about the drum. Secured to the lower end of the webbing 35 is a strip of tape 38 provided with eyelets or grommets 39 through which cords or laces 40 may be threaded, which members pass through complementary grommets 41 in the actual curtain or cyclorama 42, whereby the curtain is suitably supported from the bias-cut webbing 35.

Stage curtains are often of considerable height or great width in a vertical direction, and therefore are constructed of several strips of material which are overlapped and sewed together, making various horizontal seams along the curtain, as shown at 43 in Fig. 7. If it is desired that the curtain lie flat and not develop vertical wrinkles, this may be prevented by securing at various spaced positions lengths of horizontally extending steel tapes or bands 44, as shown in Figs. 6 and 7. These bands will preferably be of concavo-convex form, and they will tend to hold the curtain in a flat condition, preventing vertical wrinkles. These bands may be covered by a strip 45 of any suitable material. It will be understood that as many of these horizontal bands as necessary may be provided. Usually, however, it will only be necessary to provide them at the horizontal seams.

From inspection of Fig. 4 it will be observed that the cords or laces 40 supporting the cyclorama may, if desired, permit the latter to lie in folds below the supporting strip 38, as these cords may be arranged to take any desired direction. If it is desired to have the curtain lie in vertical folds, it will be suspended from the grommets 39 by individual cords, which cords will spread apart at their lower ends when the curtain is wound upon the drum.

The supporting track for the curtain is shown more particularly in Figs. 1, 2, and 8 to 11 of the drawings. This supporting track, as shown, comprises two tiers or rows of overlapping block-shaped members 46. As shown, the block-shaped member 46^a at the end of the flexible track adjacent the frame member 12 is secured to this frame member, so that this end of the track will be supported by the frame member. It will be noted that the frame members of one tier are slightly spaced apart, and their adjacent end portions are overlapped by the block members of the other tier. These members may be of any rigid material, either wood or metal, for example. The block members are secured together in superposed position by means of bolts 47, each block member having a bolt adjacent its ends, one of the bolts passing into one block of the other tier and the other bolt passing into a second block of the other tier, so that the blocks will be arranged in a chain-like formation but will be secured rigidly together when the bolts 47 are tightened. It will be understood that if the blocks are arranged, as shown in Fig. 8, so that they are all in a straight line, the track will be absolutely straight and will extend rigidly from the supporting member 12. This support at one end will not, however, be sufficient, and cables 48 secured to the ceiling or other overhead structure may be arranged at various points along the length of the track and serve as suspending or supporting members, these cables being secured at their lower ends to stirrups 49, which are in turn secured to the upper blocks 46.

It will also be understood that when the bolts 47 are loosened, the blocks may be adjusted with respect to each other about these bolts as pivots, so that the track may be given any desired sinuous form, as shown in Figs. 1 and 9. After the proper adjustment is secured, the bolts are again tightened so that the track will be rigid. Secured to the end block 46^b at the free end of the track is a member 50 to which the pulley 31 is secured, which pulley, as has been explained, supports the curtain cable 30. Suitable guy ropes or wires 51 may be secured to this block in order to give it additional rigidity and prevent any wearing motion of the track during the operation of the curtain. It will be noted from reference to Fig. 9 that angular adjustment of the blocks of one tier relatively to those in the same tier will be limited by the space between adjacent blocks. That is, this adjustment can be carried no further than the point shown in that figure, in which position the corner of one block is lodged against the end face of the adjacent block whereby the spacing between adjacent blocks limits the amount of relative displacement which might be effected by an external force.

Upon the blocks 46 are provided pairs of rollers or sheaves 52, these members being mounted upon vertical axes and being spool-shaped in cross-section, so that, while the cable passes freely between them, it will be prevented from being disengaged from the rollers by a vertical movement. It will be understood that rollers are provided on the upper sides of the upper blocks to carry the upper run of the cable to which the curtain is not attached, and on the lower side of the lower blocks to carry the lower run of the cable to which the curtain is attached. These lower sheaves actually serve to support the curtain by reason of the fact that the cable will be confined between them, and not be allowed to slip out, and that, as a pair of these rollers is provided adjacent each end of each block closely adjacent the pivot bolts 47, so that the cables will be properly guided and uniformly supported regardless of whether the track is adjusted to a sinuous or straight horizontal path, tension on the cable will not tend to deform the track. Moreover, it will also be observed that the diameter of the winding cable and the pitch of the threads of the shaft 15 will be so related that the drum will travel up and down to correspond with the winding of the various turns of the cable thereon, so that both upper and lower runs of the cable will be delivered to the drum at the proper height.

As shown in Fig. 1, the curtain is in its extended position. It will be noted that in that position there are a number of turns of the upper run of the cable upon the drum, for when the curtain is wound up, the upper run of the cable must be permitted to unwind. If, therefore, the shaft 15 is rotated when the parts are in the position shown in Fig. 1, the rotation of the drum will effect the winding up of the lower run of the cable, and the unwinding of the upper run. This lower run of the cable which carries the curtain will be supported by the shoulder 25 upon the drum, so that it cannot slip downwardly. When one turn of the drum has been made, the latter will be lowered by means of the threads 19 on the shaft 15, so that the next turn of the cable will be properly delivered to lie closely above the first turn, and succeeding turns will be likewise disposed. At the same time the lowering of the drum will bring the second turn of the upper run

of the cable downwardly opposite the guide sheaves 52 on the supporting track, so that they will be properly delivered thereto, and succeeding turns will likewise be brought to the proper position. The idler roller 23 will press against the cable to keep it in contact with the drum above the shoulder 25 or above a lower turn of the cable, and will hold the cable and curtain in position at this point in case the cable should break.

It will be noted that as the curtain is wound up upon the drum the diameter of the roll formed thereby will get larger and larger as succeeding turns are placed one on top of the other, and will, of course, be larger opposite the shoulder 25 than elsewhere. This enlargement, however, is readily taken care of by the stretching of the bias-cut webbing 35, so that the curtain will lie in a smooth circular roll depending freely from the drum, and may be wound up or extended without any danger of injury.

The extension of the curtain is, of course, accomplished by the rotation of the drum in the opposite direction, as will be clearly understood.

While I have shown and described a preferred embodiment of my invention, it will be understood that it is not to be limited to all the details shown, but is capable of modification and variation within the spirit of the invention and within the scope of the appended claims.

What I claim is:

1. In a device for movably suspending a sheet of thin material, a suitably supported substantially horizontally extending member, cable-guiding means on said member, a vertically arranged rotatable drum adjacent one end of said member, a cable engaged with said guiding means the ends of which are adapted to be wound on said drum, a suitably supported pulley about which the bight portion of the cable is trained, said sheet being secured to said cable, and a portion of said cable being supported as well as guided by said guiding means.

2. In a device for movably suspending a sheet of thin material, a suitably supported substantially horizontally extending member, cable-guiding means on said member, a vertically arranged rotatable drum adjacent one end of said member, a cable engaged with said guiding means the ends of which are adapted to be wound on said drum, a suitably supported pulley about which the bight portion of the cable is trained, said sheet being secured to said cable, said guiding means being disposed in sets one above and one below said member, and the run of the cable engaging the lower set having the sheet secured thereto and being supported against sagging by said guiding means.

3. In a device for movably suspending a sheet of thin material, a suitably supported substantially horizontally extending member, cable-guiding means on said member, a vertically arranged rotatable drum adjacent one end of said member, a cable engaged with said guiding means the ends of which are adapted to be wound on said drum, a suitably supported pulley about which the bight portion of the cable is trained, said sheet being secured to said cable, and said pulley being supported on the outer end portion of said member.

4. In a device for movably suspending a sheet of thin material, a suitably supported substantially horizontally extending member, cable-guiding means on said member, a vertically arranged rotatable drum adjacent one end of said member, a cable engaged with said guiding means

the ends of which are adapted to be wound on said drum, a suitably supported pulley about which the bight portion of the cable is trained, said sheet being secured to said cable, and said member being articulated whereby its shape may be changed in the direction of its length.

5. In a device for movably suspending a sheet of thin material, a suitably supported substantially horizontally extending member, cable-guiding means on said member, a vertically arranged rotatable drum adjacent one end of said member, a cable engaged with said guiding means the ends of which are adapted to be wound on said drum, a suitably supported pulley about which the bight portion of the cable is trained, said sheet being secured to said cable, and said supporting member comprising jointed sections secured together for relative adjustment in a direction transverse to the longitudinal dimension of said member.

6. In a device for movably suspending a sheet of thin material, a suitably supported substantially horizontally extending member, cable-guiding means on said member, a vertically arranged rotatable drum adjacent one end of said member, a cable engaged with said guiding means the ends of which are adapted to be wound on said drum, a suitably supported pulley about which the bight portion of the cable is trained, said sheet being secured to said cable, said supporting member comprising jointed sections secured together for relative adjustment in a direction transverse to the longitudinal dimension of said member, and means for securing said sections rigidly together after adjustment to predetermined positions.

7. In a device for movably suspending a sheet of thin material, a suitably supported substantially horizontally extending member, cable-guiding means on said member, a vertically arranged rotatable drum adjacent one end of said member, a cable engaged with said guiding means the ends of which are adapted to be wound on said drum, a suitably supported pulley about which the bight portion of the cable is trained, said sheet being secured to said cable, said member comprising sections pivoted together for relative movement one with respect to another, and means for rigidly securing said sections in a given position of adjustment to form a rigid structure.

8. In a device for movably suspending a sheet of thin material, a suitably supported substantially horizontally extending member, cable-guiding means on said member, a vertically arranged rotatable drum adjacent one end of said member, a cable engaged with said guiding means the ends of which are adapted to be wound on said drum, a suitably supported pulley about which the bight portion of the cable is trained, said sheet being secured to said cable, and a portion of said cable being supported as well as guided by said guiding means, said drum having an annular shoulder thereon to support the turns of the cable from below.

9. In a device for movably suspending a sheet of thin material, a suitably supported substantially horizontally extending member, cable-guiding means on said member, a vertically arranged rotatable drum adjacent one end of said member, a cable engaged with said guiding means the ends of which are adapted to be wound on said drum, a suitably supported pulley about which the bight portion of the cable is trained, said sheet being secured to said cable, a portion of said cable being supported as well as guided

by said guiding means, and means for moving said drum in a vertical direction during the rotation thereof.

10. In a device for movably suspending a sheet of thin material, a suitably supported substantially horizontally extending member, cable-guiding means on said member, a vertically arranged rotatable drum adjacent one end of said member, a cable engaged with said guiding means the ends of which are adapted to be wound on said drum, a suitably supported pulley about which the bight portion of the cable is trained, said sheet being secured to said cable, said member comprising a plurality of sections arranged in upper and lower tiers, and each section of one tier having its ends overlapping the adjacent sections of the other tier and attached thereto.

11. In a device for movably suspending a sheet of thin material, a suitably supported substantially horizontally extending member, cable-guiding means on said member, a vertically arranged drum adjacent one end of said member, a cable engaged with said guiding means the ends of which are adapted to be wound on said drum, a suitably supported pulley about which the bight portion of the cable is trained, said sheet being secured to said cable, said member comprising a plurality of sections arranged in upper and lower tiers, and each section of one tier having its ends overlapping the adjacent sections of the other tier and adjustably secured thereto for relative movement in a direction transverse to the longitudinal dimension of the member.

12. In a device for movably supporting a curtain or like sheet of material, a substantially horizontally disposed supporting member, a cable supported by said member, a drum adjacent one end of the member upon which the cable is adapted to be wound, a strip of bias-cut webbing secured to the cable, and a curtain supported by said webbing whereby said webbing may stretch when wound upon the drum.

13. In a device for movably supporting a curtain or like sheet of material, a substantially horizontally disposed supporting member, a cable supported by said member, a drum adjacent one end of the member upon which the cable is adapted to be wound, a strip of webbing secured to said cable, a curtain secured to the webbing, and the threads of said webbing extending at an angle to the horizontal to permit the curtain to be wound evenly on said drum.

14. In a device for movably supporting a curtain or like sheet of material, a substantially horizontally disposed supporting member, a cable supported by said member, a drum adjacent one end of the member upon which the cable is adapted to be wound, a strip of bias-cut webbing secured to the cable, a curtain, and laces securing said curtain to the webbing to freely suspend the curtain therefrom.

15. In a device for movably supporting a curtain or like sheet of material, a substantially horizontally disposed supporting member, a cable supported by said member, a drum adjacent one end of the member upon which the cable is adapted to be wound, a curtain suspended from said cable, and wrinkle-preventing means secured to said curtain, said means comprising a plurality of stiffening strips each extending horizontally across the curtain and arranged in spaced relation vertically thereof.

16. In a device for movably supporting a curtain or like sheet of material, a substantially

horizontally disposed supporting member, a cable supported by said member, a drum adjacent one end of the member upon which the cable is adapted to be wound, a curtain suspended from said cable, and wrinkle-preventing means secured to said curtain, said means comprising a plurality of stiffening strips each extending horizontally across the curtain and arranged in spaced relation vertically thereof, and said strips comprising thin metallic members of concavo-convex form in cross section.

17. In a device for movably supporting a curtain or like sheet of material, a substantially horizontally disposed supporting member, a cable supported by said member, a drum adjacent one end of the member upon which the cable is adapted to be wound, a strip of bias-cut webbing flexibly secured to the cable to be restrained against longitudinal movement thereon, and a

curtain supported by said webbing whereby said webbing may stretch when wound upon the drum.

18. In a device for movably supporting a curtain or like sheet of material, a substantially horizontally disposed supporting member, a cable supported by said member, a strip of bias-cut webbing secured to the cable for a portion of the length of the latter, a curtain secured to the webbing, a multiple diameter drum adjacent one end of the supporting member, the portion of said cable to which the webbing is secured being wound upon one portion of the drum and the bare cable being wound upon a drum portion of different diameter, said bias-cut webbing permitting portions of the cable to be wound evenly on the drum.

DAVID A. WASHBURN.
